SNOW THROWER

Charles A. Mattson, Oak Park, Ill., and Fredrick O. Ottosen, deceased, late of Chicago, Ill., by Harriet Ottosen, executrix, Chicago, Ill., assignors to Sunbeam Corporation, Chicago, Ill., a corporation of Illinois

Filed Feb. 14, 1963, Ser. No. 73,577

Term of patent 14 years

(Cl. D35—2)

Fig. 3

Fig. 2

Fig. 4

Fig. 5

*Fig. 5**Fig. 7*FIG. 1 is a perspective view of the snow thrower embodying our new design;

FIG. 2 is a front elevational view;

FIG. 3 is a right side elevational view;

FIG. 4 is a rear elevational view;

FIG. 5 is a left side elevational view;

FIG. 6 is a top plan view; and

FIG. 7 is a bottom plan view.

The essential features of the design reside in the portions shown in solid lines. Aside from FIG. 1 the views of the drawings show some of the broken line portions fragmentarily and other broken line portions omitted for convenience of illustration.

We claim:

The ornamental design for a snow thrower, substantially as shown and described.
